UNITED STATES PATENT OFFICE.

HARRY W. HEPNER, OF ALLENTOWN, PENNSYLVANIA.

POLISHING-MITT.

1,139,283.

Specification of Letters Patent   Patented May 11, 1915.

Application filed May 12, 1914.   Serial No. 838,058.

To all whom it may concern:

Be it known that I, HARRY W. HEPNER, a citizen of the United States, and a resident of Allentown, in the county of Lehigh and 5 State of Pennsylvania, have invented a new and Improved Polishing-Mitt, of which the following is a full, clear, and exact description.

Among the principal objects which the 10 present invention has in view are: to provide an article of the character mentioned with a tubular brush affording a number of surfaces, adapted for special employment; to provide a wallet-like container for said 15 brush, foldable to facilitate personal carriage or the packing within a satchel or trunk; and to provide a device as characterized having means for carrying a toilet equipment.

20 *Drawings.*—Figure 1 is a perspective view of a mitt constructed and arranged in accordance with the present invention; Fig. 2 is a side view of the same; Fig. 3 is a cross section taken on the line 3—3 in Fig. 25 2; Fig. 4 is a horizontal section taken on the line 4—4 in Fig. 2; Fig. 5 is a side view of the mitt, the view being taken from the side opposite that illustrated in Fig. 2, the brush section being extended in service arrangement; Fig. 6 is a section taken as on the line 6—6 in Fig. 5, showing in connection therewith and in dotted lines the hand 30 of a user of the brush section.

35 *Description.*—As seen in the accompanying drawings, the tubular extension which constitutes the double brush herein mentioned, has a half-section 11, preferably constructed from heavy-nap velvet or short-nap plush, to provide a bristly surface 12, 40 adapted for use on the clothes or hat of a person. The opposite half-section 13 is provided externally with a suitable material for rubbing or otherwise cleaning the shoes of the person. The two sections are 45 united lengthwise to form joints 15. Between the edges of the joints 15, and midway of the length of the extension, is disposed a holding strap 16. The strap 16 is somewhat lengthened to permit the insertion 50 thereof between the fingers of the wearer, to serve as a gripping member for the hand when using the brush.

The tubular extension is sewed to the edge 17 of an open-ended pocket 18. When not

in use, the half sections 11 and 13 are flattened down upon each other and turned to be inserted in the pocket 18, which thereafter serves as a protection for and against said sections.

The outer wall of the pocket 18 is doubled, 60 having an outer layer 19. Between the wall of the pocket 18 and the outer layer 19 is provided a folded member 20, which is divided lengthwise by lines of stitching 21 and 22 to form pockets or receptacles of 65 different widths. It will be noted that the open ends of said pockets formed by the stitching 21 and 22, are turned upward or toward the wrist of the user of the brush when the same is disposed in service, as 70 shown best in Fig. 6 of the drawings. The pockets thus formed are provided to receive such toilet articles as shoe buttons, combs and other articles.

When the mitt is packed, and the brush 75 extension is inclosed in its pocket 18, said mitt may be folded lengthwise, as seen best in Fig. 1 of the drawings, and in this condition is placed in a satchel or other receptacle, or carried in the pocket. 80

While I have herein described the invention as employing a tubular member as a brush, and have further indicated the preferred construction as having faces formed from different materials, I do not wish to be 85 so limited, as it is evident that a material folded, instead of constructed in the tubular form, may be employed, and that said material may be faced with the same material throughout. 90

Claims:

1. A mitt comprising a tubular toilet brush having rubbing surfaces constructed of different materials to serve a variety of uses; and a containing pocket for said brush, said pocket being hinged to said brush. 95

2. A mitt comprising a tubular toilet brush having rubbing surfaces constructed of different materials to serve a variety of 100 uses; and a containing pocket for said brush, said pocket being hinged to said brush, the sides of said pocket completely covering said brush.

3. A mitt comprising a tubular toilet 105 brush having rubbing surfaces constructed of different materials to serve a variety of uses; and a containing pocket for said brush,

said pocket being hinged to said brush, said brush and said pocket being co-extensive, the sides of said pocket completely covering said brush, said pocket being provided at 5 one side with two overlaid walls, the space between said walls being divided to form a series of end-opening pockets.

Copies of this patent may be obtained for five cents each, by addressing the "Commissioner of Patents, Washington, D. C."

In testimony whereof I have signed my name to this specification in the presence of two subscribing witnesses.

HARRY W. HEPNER.
